NEUROSTIMULATION TRANSMITTER OR THE LIKE

Roger E. Avery, Melville, N.Y., assignor to Avery
Laboratories Inc., Farmingdale, N.Y.

Filed June 14, 1971, Ser. No. 153,129

Term of patent 14 years

Int. Cl. D24—02

U.S. Cl. D83—1 F

FIG. 1

FIG. 2

FIG. 3

FIG. 4

FIG. 5

FIG. 1 is a perspective view showing my neurostimulation transmitter;

FIG. 2 is an end view taken in elevation, both ends being identical;

FIG. 3 is a side view taken in elevation, both sides being identical;

FIG. 4 is a top plan view thereof; and

FIG. 5 is a bottom plan view thereof.

I claim:

The ornamental design for a neurostimulation transmitter or the like, substantially as shown and described.
